(57) **CLAIM**

The ornamental design for a specimen cutting apparatus, as shown and described.

DESCRIPTION

FIG. 1 is a perspective view of the top, front and right side of a specimen cutting apparatus showing our new design;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof; and,

FIG. 8 is a perspective reference view with the lid in open condition thereof.

The broken lines shown in the interior of specimen cutting apparatus in FIG. 8 are included for the purpose of illustrating portions of the specimen cutting apparatus that form no part of the claimed design.
